ORE CONCENTRATOR

Charles M. Fuller, Los Angeles, Calif., assignor to
E. D. Wilkinson, Stockton, Calif.

Application June 6, 1936, Serial No. 83,908

12 Claims. (Cl. 209—475)

This invention relates to ore concentrators and has for its objects the provision of apparatus for handling value bearing ore in a dry condition for separating the heavier values therefrom by 5 pneumatic means in combination with ore concentrating tables having tensioned membrane tops and riffles arranged for entrapping the values from ore passing over such tops and means for releasing the entrapped values to prevent excessive accumulation of values with the tailings. Other objects are the provision of means for facilitating the separation of so called "flour" gold from sand or ore and for accelerating the separation of all values of various sizes from 10 the ore. Other objects and advantages will appear in the drawings and description annexed hereto.

In the drawings,

Fig. 1 is an elevational, semi-diagrammatic view 20 of a complete ore concentrating plant with part broken away to reveal several of my improved ore concentrating tables.

Fig. 2 is a vertical sectional view taken along the line 2—2 of Fig. 1.

Fig. 3 is an enlarged, fragmentary sectional view showing the construction of the tables in detail, and also the air lines connecting with the tables and the ore feeding arrangement for feeding ore to the tables.

Fig. 4 is a fragmentary sectional view taken through one of the tables along a line 4—4 of Fig. 3.

Fig. 5 is a fragmentary sectional view taken through one of the tables along the line 5—5 of Fig. 3, omitting the riffle.

Fig. 6 is a plan view of one of the tables on one side of the central air line extending between the two rows of tables, with a portion of the table on the opposite side of the air line 40 in section. Portions are broken away and in section for clarity.

Fig. 7 is an enlarged end view of one of the riffles with a portion of the table construction in section.

Fig. 8 is an elevational view of the riffle of Fig. 7, centrally broken to accommodate the view to the sheet.

Fig. 9 is a fragmentary elevational view of another form of riffle, the same as that of Fig. 8, except for the omission of the holes and saw-tooth or notched lower edge.

In detail, each of the concentrator tables comprises a plurality of tensioned strips 1 of fabric or other suitable porous membranous material, 55 said strips being disposed in an inclined plane

in a row extending from the elevated end of the plane toward the lowered end. The strips are tightly stretched over the upper edges of pairs of spaced plates 2, which plates are disposed with their sides substantially vertical, said pairs 5 of plates being spaced from the pair adjacent thereto, leaving a vertically opening horizontal passageway 3 between each of said pairs of plates and the fabric strips secured thereto.

The margins of the strips are drawn down over 10 the outer sides of the plates of each pair and secured against the outer sides by metal strips 5, 5'. The successive plates from the lower end of the table toward the elevated end are of progressively higher elevation at their upper edges 15 so as to give the proper inclination to the upper surface of the table top as defined by the upper surface of the strips. The metal clamping strip 5 is the strip engaging the plate 2 of lowest elevation of each pair and strip 5' is the strip engaging the higher plate. The upper edge of metal strip 5 is slightly below the plane of the fabric strip that it serves to clamp against the lower plate 2 and the upper edge of strip 5' is elevated above the plane of the strip that it serves to 20 clamp to the upper plate 2. This arrangement of strip 5, in particular, will be later explained more in detail, since it serves a useful purpose.

Side walls 6 extend over the outer ends of plates 2 and the end margins of the fabric strips, said 30 walls extending upwardly to engage at their upper edges with a cover 7, and an end plate 8 extends vertically across the lower end of the table, but spaced therefrom to permit tailings to pass between the end plate and table. An inclined bottom plate 9 connects with the end plate 8 at the upper edge thereof and leads to a conveyor 35 9 for carrying the tailings away.

Extending between side walls 6 and over the space 3 between the adjacent plates 2 of adjacent pairs of said plates are transversely extending riffle bars 10, commonly called "riffles", which riffles are generally of inverted Y shape in cross section, best seen in Fig. 7. One arm 11 of the Y lies over the upwardly projecting 40 edge of metal strip 5, with its sides substantially vertical, and the other arm 12 of the Y engages at its lower edge against the upper edge projects toward strip 5'. The leg 13 projects toward the end of the table and in a plane substantially 45 coincident with the arm 12.

The ends 14, 14' of the riffle are in extension of the arm 12, and are cylindrical. Said ends rotatably pass through side plates 6. The end 14' of each riffle is slightly longer than the end 14 55

for a purpose later to be described. Along its lower edge, the arm 11 may be notched or cut away to generally a saw-tooth formation as at 15 and openings 16 may be formed therethrough 5 above the notches, if desired.

From the foregoing, it will be seen that the arm 11 of the Y, is a sort of vertically disposed, horizontally elongated flange, and is the portion 10 of the rifle that provides a working face on the side facing the elevated end of the table for obstructing the downward passage of the heavier values over the table and the leg of the Y overhangs the strip 5 and plate 2 adjacent the working face of the rifle to form a sort of pocket 18 15 removed from the influence of blasts of air that are directed upwardly through the fabric strips 1, as will be explained later.

On the ends 14' of the rifles are vertically extending crank arms 19, said arms being pivotally 20 connected at their upper ends to an elongated bar 20 slanted to the same degree as the table, the upper end of said bar being at the head of the table or elevated end thereof, and the lower end being adjacent the lower end of the 25 table. A lever 21, adjacent the lower end of the bar, projects vertically through a slot in cover 7, and is pivotally connected, at 22 to the bar, and to side plate 6 at 22', for revolving all the rifles simultaneously, thereby lifting the flange 30 11 of the rifles to allow the values adjacent the working face thereof to fall, through space 3 between the adjacent pairs of plates 2, to an inclined chute 23 leading outwardly at 24 through the bottom plate 8' for collecting on a conveyor 35 or a suitable container, not shown.

It is important to note that the position of the upper edge of strip 5, below the plane of the fabric strip 1 adjacent thereto, precludes any chance of small particles of gold or other 40 values becoming lodged against the working face of flange 11 in such a manner as to prevent the release of such values upon revolving the rifle to raise flange 11 relative to strip 5.

While I show the flange 11 with a notched 45 lower edge for continuously "bleeding" values into space 3, the lower edge of the flange may be straight, and spaced from strip 5 by means of an adjustable bolt 30 on a bracket 31 at the upper end of the table (see Fig. 3) which bolt 50 engages at its outer end the upper end of bar 20 that connects the crank arms. The rifles tend to drop automatically to close along adjacent edges of flanges 11 and strips 5, even when ore 55 is passing over the tables, hence by adjusting bolt 30, and locking it by nuts, as shown, in an adjusted position, a small width slot or a large one may be maintained between strips 5 and flanges 11, respectively, and this adjustable feature is desirable even when the lower edges of 60 the flanges are notched. The openings in the flanges above the notches serve as auxiliary "bleed" means for use as such in certain cases where the flanges are relatively wide and are less frequently raised to pass the entrapped values 65 to space 3.

Below the fabric strips 1, and extending longitudinally of each table is an air conduit 32 (Fig. 5), which conduit is cut away, at those 70 portions between the plates 2 of each pair of plates, on the upper side thereof so as to permit free communication of air between the conduit and the area below each of the fabric strips 1, while below the rifles, or between the adjacent plates of pairs of plates, the top of the 75 conduit is closed by an inverted V-shaped top

32' so that values released to fall into space 3 will be deflected to opposite lateral sides of the conduit for falling onto the bottom 23 for discharge through opening 24.

The vertical cross-sectional area of conduit 5 32 progressively decreases from the end thereof 10 adjacent the elevated end of the table toward the lower end, which lower end is provided with a valve 33 for regulating the effective pressure 15 or suction force of air in the conduit according to whichever is applied.

At their upper ends the conduits 32 connect 20 respectively with valves 34, that are fitted with power operated rotary valve members later described, and an air pressure line 35 extending 15 along the row of valves communicates with each of the valves, a power operated blower 36 being operatively connected to line 35 at one end thereof as seen in Fig. 1.

Above the valves 34 and communicating therewith is an air suction conduit 37. This conduit has straight sides and an inverted V-shaped top, the sides of which are provided with openings 38, each of which communicates with the area above the fabric strips 1 and cover 7. A 25 suction blower 39 serves to produce suction in said conduit 37 and to draw dust from above strips 1 through openings 38 for discharge to a stack 38' or dust collector.

The valves 34 are each fitted with a horizontal, cylindrical valve member 40 (Fig. 6), which members are secured on a horizontal, rotatably mounted shaft 41 that extends through opposite sides of the valve casings respectively and which shaft is rotated through suitable reduction gearing 43 at one end thereof, said gearing being driven from the motor 44 of the suction blower or by a separate motor, if desired, the shaft normally being rotated at about 150 30 R. P. M. 40

Each of the valve members 40 is divided by a vertical partition 42, and the cylindrical wall at opposite sides of the partition is formed with openings 45, 46, one opening at each side. Ports 47, 48 are formed in opposite lateral side walls 45 of the valve 34 and a vertically downwardly directed port 49 is formed in the bottom wall of the valve casing. Ports 47, 48 are adapted to register with both of the openings 45, 46 upon rotation of the valve member as said openings 50 pass the ports, but the port 49 will register with opening 45 only. The ports 47, 48 communicate with conduits 32 that extend below the fabric strips 1 of the tables, while port 49 communicates with the air pressure line 35 only. 55

The upper side of the valve body is formed with a port 50 off-set relative to port 49 to communicate with the opening 46 only, when the body is rotated to bring the opening over the port. Said port 50 communicates with the air 60 suction conduit 37.

The openings 45, 46 are of a size relatively, and are positioned relatively around the cylindrical member 40, so as to form an alternate pressure and suction communication between pressure line 65 35, suction conduit 37, and the air conduits 32 below strips 1 of the tables, as the member 40 is rotated.

Ore is fed onto the tables through openings 51 at the lower edges of an inverted V-shaped bottom 52 that is spaced above the inverted V-shape top of suction conduit 37, from which openings 70 vertical passageways 53 lead to over the elevated ends of the tables for discharge thereon. Inclined side walls 54 extend upwardly and outwardly of 75

the upper ends of the passageways, which inclined walls connect at their lower edges with the lower edges of the bottom 52 between the passageways. Feed to said passageways is controlled by sliding gates 55, operated for opening and closing, by pivotally connected links 56, mounted on brackets 57, as best shown in Fig. 2.

Any suitable means may be used for delivering ore to said passageways, such as conventional 10 elevator 58 feeding to a spout 59 that discharges into an inclined distributing screen 60.

In operation, it will be seen that as ore is fed onto the fabric strips of the tables for passage thereover and over the riffles to the lower ends 15 of the tables, the ore will be subject to intermittent upward blasts of air passing through the strips, causing agitation of the ore and a lifting of the lighter particles with a settling of the heavier particles to the upper surface of the 20 strips of fabric. This is common practice.

Heretofore considerable loss of values has resulted from the piling up of values and ore along the working face of the riffles, with the result that some of the values go over the riffles 25 and are discharged with the tailings, and also the fine "flour" gold, where gold comprises the values, is also carried upwardly above the upper edges of the riffles. If the gold particles, which are heavier than the valueless ore, are maintained 30 sufficiently close to the fabric to be caught by the riffles, and are thereafter out of the influence of the upward force of the air blasts passing through the fabric, and are removed from the path of travel of the main body of ore, they will be saved 35 from loss with the tailings. It is these things that I accomplish, since by immediately changing the force below the fabric ore supporting top of the table from pressure to vacuum or suction, the finer particles of gold that would ordinarily 40 be kept in suspension above the top by reason of the residual air pressure maintained between blasts are quickly brought back to against the fabric, or at least below the level of the top edges of the riffles and when these particles work downwardly on the table to the working face of the riffles, they will accumulate against the working 45 faces of the riffles respectively and in the dead air space 18 where the blasts of air will not affect them. From this pocket they will continuously 50 filter between the riffles and metal strips 5 to space 3, from which space they are carried away for further treatment or for storage. When ore accumulates adjacent the riffles to tend to obstruct 55 free passage of values to the space 3, the revolving of the riffles immediately clears the obstruction. Preferably the feed gates to the tables are closed during revolution of the riffles so as to facilitate revolving the riffles back to operative 60 position.

It is to be particularly noted that my device is particularly adapted for use with dry ore, by the dry process of concentrating values which differs considerably from the wet processes, although the use of concentrating tables including 65 riffles is common in both processes.

I am not aware of there having been any previous attempts to carry the dust away from the tables of dry concentrators and to utilize this feature to augment the effect of the blasts of air used to agitate the ore and to separate the lighter material from the values. In my device, the fact that there are periods when suction is applied above and below the table top at the same time does not neutralize the effect of the suction below 70 the table in keeping the values close to the table, 75

since the air conduit below the table top is fully enclosed and the layer of ore on the table is of a material thickness to tend to form a top seal over the top of the table, while the area over the table is not so enclosed as air is free to enter through slots in the cover that pass the riffle operating handles and also air may enter through the passageway that carries the tailings away. But the suction force above the tables is sufficient to carry away light dust that would otherwise accumulate 10 and be detrimental to health as well as detrimental to the efficiency of the apparatus for concentrating the values.

Having described my invention, I claim:

1. In ore concentrating apparatus, an inclined ore concentrating table adapted to support ore thereon for movement on the upper surface thereof in a direction from the elevated end of the table toward the lowered end thereof, a plurality of elongated riffles adjacent the upper surface of the table extending transversely of the normal directional movement of the ore for obstructing free passage of ore over the table, means mounting said riffles for movement simultaneously generally vertically relative to the table for allowing obstructed ore on the table to pass the riffles, and means for so moving said riffles, said riffles being spaced a small distance apart relative to the length of the riffles and the space between adjacent riffles being unobstructed for free movement of ore on the table.

2. In ore concentrating apparatus, an ore concentrating table provided with a top comprising a plurality of relatively narrow spaced strips of porous tensioned fabric arranged respectively with a flat side uppermost and with the flat upper sides disposed in an inclined plane for forming an inclined upper surface on said top, adapted to support value bearing ore thereon for normal directional movement from the elevated end 40 of the top toward the lowered end, said strips extending transversely of said normal directional movement of the ore whereby one side edge of each strip is elevated above the opposite side edge thereof, means for supporting said strips 45 spaced apart, and movable means, including upstanding riffles, arranged for obstructing free passage of ore over the spaces between adjacent strips to separate ore values upon movement of ore over said strips, the upper sides of the strips 50 being unobstructed for free movement of the ore thereon between adjacent riffles.

3. In ore concentrating apparatus, an ore concentrating table provided with a top comprising a plurality of spaced, relatively narrow strips of porous tensioned fabric arranged respectively with a flat side uppermost and with the flat upper sides disposed in an inclined plane for forming an inclined upper surface on said top, adapted 55 to support value bearing ore thereon for normal directional movement from the elevated end of the top toward the lower end, said strips extending transversely of said normal directional movement of the ore whereby one side edge of each strip is elevated above the opposite side edge thereof, means for supporting said strips spaced apart, and means, including upstanding riffles, arranged for obstructing free passage of ore to the spaces between adjacent strips upon 70 movement of ore over said strips, the upper sides of the strips between riffles being unobstructed for free movement of the ore over the strips to the riffles, means for moving said riffles relative to the strips in a direction for permitting ore to 75

pass by the riffles to the spaces between the strips.

4. In ore concentrating apparatus, an ore concentrating table provided with a top comprising a plurality of spaced, relatively narrow, strips of porous tensioned fabric arranged respectively with a flat side uppermost and with the flat upper sides disposed in an inclined plane for forming an inclined upper surface on said top, adapted to support value bearing ore thereon for normal directional movement from the elevated end of the top toward the lower end, said strips extending transversely of said normal directional movement of the ore whereby one side edge of each strip is elevated above the opposite side edge thereof, means for supporting said strips spaced apart, and means, including upstanding riffles, arranged for obstructing free passage of ore to the spaces between adjacent strips upon movement of ore over said strips, the upper sides of the strips between riffles being unobstructed for free movement of the ore over the strips to the riffles, means for causing pulsations of air upwardly through said strips, and means, adjacent each of the riffles on the side thereof facing generally toward the elevated side edge of the strip positioned adjacent thereto arranged and adapted for obstructing the upward passage of air for creating a dead air space adjacent each of the riffles.

5. In ore concentrating apparatus, a table having an inclined top adapted for supporting value bearing ore thereon for movement from the elevated end in a direction toward the lowered end, said top being formed with elongated, vertically directed, openings extending in a direction transversely of the normal directional movement of the ore, riffle bars extending longitudinally of the openings and thereover, bearings revolvably mounting said riffle bars respectively at their opposite ends, at the inclined side edges of the table, means arranged for revolving said bars therein about axes extending longitudinally of the bars, a portion of each of said riffle bars being off-set relative to the axis of rotation thereof, said portion extending substantially from side to side of the table top and disposed adjacent an edge of the opening adjacent the riffle, whereby upon revolving the bar said portion will be moved away from the edge of the opening for permitting ore to pass between said portion and edge and into said opening.

6. In a construction as defined in claim 5, said top being of porous tensioned fabric, suction means above said top continuously operative for drawing dust from above the top, and air pressure means operative below said top arranged for causing upwardly directed blasts of air through said fabric at intervals.

7. In a concentrating apparatus of the character described, a table having an inclined top of porous tensioned fabric adapted for supporting ore thereon for movement normally in a direction from the elevated end of the table toward the lowered end, a plurality of elongated riffles extending across the top of the table in a direction from side to side of the table transversely of the normal directional movement of the ore, each of said riffles being formed with a flange portion extending longitudinally thereof and in a generally vertically disposed plane and projecting above the plane of the top for providing a working face along one side thereof facing the elevated end of the top, the lower edge of said flange portion being normally disposed adjacent the top of said table whereby said por-

tion will normally obstruct the free movement of ore over the top, means pivotally mounting said riffles respectively for movement of the flange portion generally vertically relative to the top of the table in an arcuate path for freeing ore engaging along the working face thereof, and means adjacent said riffles arranged and adapted for passing the ore thus freed in a direction away from the table top.

8. In ore concentrating apparatus, a plurality of separate, similarly inclined, concentrating tables arranged in a row with their elevated and lowered ends respectively disposed in horizontal alignment, the tops of said tables being formed of tensioned porous fabric, an air suction and an air pressure line extending longitudinally of the row of tables, cover means spaced above the tops of the tables including walls extending downwardly to the sides of the tables and to the lowered ends of the tables enclosing the area above the tables and means enclosing the area below the tops of said tables, the air pressure line communicating with the enclosed area below said table tops and the air suction line communicating with the area above the tables, means for feeding ore onto the elevated ends of the tables and means for carrying ore away from the lowered ends of the tables, a plurality of riffles extending across the tables and projecting above the fabric top thereof arranged for obstructing the passage of heavier ore values from the elevated to the lowest ends of the tables, the tops of the tables being provided with openings therethrough for permitting passage of the ore values therethrough to below the tops respectively, said riffles normally substantially closing said openings, and means for simultaneously elevating the riffles of each of the tables for uncovering said openings whereby the ore values accumulated against said riffles will fall through said openings.

9. In a concentrating apparatus of the character described, a table having an inclined top of porous tensioned fabric adapted for supporting ore thereon for movement normally in a direction from the elevated end of the table toward the lowered end, a plurality of elongated riffles extending across the top of the table in a direction from side to side of the table transversely of the normal directional movement of the ore, each of said riffles being formed with a flange portion extending longitudinally thereof and in a generally vertically disposed plane and projecting above the plane of the top for providing a working face along one side thereof facing the elevated end of the top, the lower edge of said flange portion being normally disposed adjacent the top of said table whereby said flange portion will normally obstruct the free movement of ore over the top, means mounting said riffles respectively for movement of the flange portion generally vertically relative to the top of the table for freeing ore engaging along the working face thereof, and means adjacent said riffles arranged and adapted for passing the ore thus freed in a direction away from the table top, the means mounting said riffles including aligned short stub shafts projecting from opposite ends of the riffles, bearings rotatably mounting said shafts, said shafts being off-set relative to the flange portion of the riffles respectively and means for revolving the riffles including their flange portions on said shafts whereby the flange portion of each rifle will move in

- an arcuate path of travel around the axis of rotation of the shafts at its opposite ends.
10. In ore concentrating apparatus, an elongated table formed with a plurality of pairs of spaced, elongated plates disposed with their sides vertical and substantially parallel and extending transversely of the length of the table, a tensioned sheet of porous fabric extending across the top edges of each of the pairs of plates and secured thereto, leaving an elongated open space between said adjacent pairs of plates, an elongated riffle bar over each of the openings between the pairs of plates, said plates being arranged to support the fabric sheets on adjacent bars there- 15 of in a single inclined plane extending longitudinally of the table and said riffle bars each being formed with a flange portion therealong extending vertically upwardly from the side of the opening toward the elevated end of the plane 20 in which the sheets of fabric are disposed with the lower edge of the flange portion adjacent the upper edge of one of said plates thereby providing a working face for ore on the sheet on the side of the flange facing toward the elevated 25 end of the sheet, means for supporting said flange portions at various points of elevation above the plane in which the sheets are disposed for permitting a relatively small amount of material on said sheets to pass between said flange portions 30 to the open space between the pairs of plates, the working faces of the flange portions being exposed from end to end of the riffles for free passage of ore on the sheets past the flange portions at any point therealong when the flange 35 portions are supported elevated above the plane of the sheets.
11. In combination with a construction as set forth in claim 10, means for causing intermittent blasts of air below said fabric sheets, and between the plates of each of said bars, for upward movement of the air through the fabric sheets. 5
12. In ore concentrating apparatus, a plurality of separate similarly inclined concentrating tables arranged in a row with their elevated and lowered ends respectively disposed in horizontal 10 alignment, the tops of said tables being formed of tensioned porous fabric, an air suction and an air pressure line extending longitudinally of the row of tables, cover means spaced above the tops of the tables, including walls extending down- 15 wardly to the tables and to the lowered ends of the tables enclosing the area above the tables and means enclosing the area below the tops of said tables, said air pressure line connecting with the enclosed area below the tables, means for 20 feeding ore into the elevated ends of the tables and means for carrying ore away from the lowered ends of the tables, a plurality of riffles extending across the tables projecting above the fabric top thereof, arranged for obstructing the 25 passage of heavier ore values from the elevated to the lowered ends of the tables, the tops of said tables being provided with openings therethrough for permitting passage of said ore values therethrough to below said top, said riffles normally, substantially closing said openings, and means for simultaneously elevating the riffles of each of the tables for uncovering said openings whereby the ore values accumulated against said riffles will fall through said openings. 30 35

CHARLES M. FULLER.
